UNITED STATES PATENT OFFICE.

ARTHUR L. HALLIDAY, OF NEW YORK, N. Y., ASSIGNOR TO THE BIGELOW CARPET COMPANY, OF CLINTON, MASSACHUSETTS.

DESIGN FOR CARPET.

SPECIFICATION forming part of Design No. 12,199, dated March 29, 1881.

Application filed February 3, 1881. Term of patent 3½ years.

To all whom it may concern:

Be it known that I, ARTHUR L. HALLIDAY, of the city of New York, county of New York, and State of New York, have invented a new 5 and original Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

The design consists of the group A, having near its center, the figure E, shaped somewhat like an open flower. Supported on a stem projecting from the figure E branches in one direction the circular leaf-like figure B. In another direction, and on another stem, projects from the figure E the leaf-like serrated figure G, and on a stem apparently growing from the stem of the figure G grows the serrated semicircular leaf-like figure C. Upon still another stem projecting from the figure E hangs the irregular figure F, and on a stem apparently growing from the stem of the figure B hangs the figure D, showing a banded pattern, and having hanging from it the projection e. The figure d is on a stem apparently projecting from the figure B, and from d appears to hang 30 the small irregular figure g. On another stem, running around the figure B, stands the irregular figure a, and on a stem projecting from the figure d stands the figure H, resembling a cluster of leaves, while on a stem projecting from the figure G is set the figure b, containing serrated leaf-like figures.

The effect of the design is that of vine-like stems running over the body of the carpet, on which are found, at intervals, the figures described.

40

I claim—

1. The design for carpets, consisting of the figure E, substantially as shown.
2. The design for carpets, consisting of the figure B, substantially as shown.
3. The design for carpets, consisting of the figure G, substantially as shown.
4. The design for carpets, consisting of the figure D, substantially as shown.
5. The design for carpets, consisting of the figure C, substantially as shown.
6. The design for carpets, consisting of the figure F, substantially as shown.
7. The design for carpets, consisting of the figure d, substantially as shown.
8. The design for carpets, consisting of the figure H, substantially as shown.
9. The design for carpets, consisting of the figures E, G, and C, substantially as shown.
10. The design for carpets, consisting of the figures G, E, and B, substantially as shown.
11. The design for carpets, consisting of the figures G, E, B, and C, substantially as shown.
12. The design for carpets, consisting of the figures D and e, substantially as shown.
13. The design for carpets, consisting of the group A, composed of figures E, G, C, F, D, e, B, a, d, g, b, and H, substantially as shown.
